BACKING ROLL FOR SHEET OR PACK ROLLING MILLS

Alexander Paterson, Buffalo, N. Y.

Application February 6, 1933, Serial No. 655,417

11 Claims. (Cl. 80—38)

This invention relates to mills for use in connection with sheet and tin plate rolling and more particularly the invention is concerned with improvements in backing rolls therefor of the kind disclosed in my co-pending application, Ser. No. 582,208, filed December 21, 1931.

In the rolling of sheet metal the working rolls, i. e., the rolls which provide the reducing pass, are deflected at their centers owing to the bending stresses set up during each reduction. As the magnitude of the reductions decreases, the magnitude of the deflections decreases correspondingly. The sheet or pack, therefore, approaches a flat or rectangular form as its thickness is reduced. Heretofore, it has been the practice to employ backing rolls in connection with the working rolls, the former cooperating with the latter to maintain the deflection of the working rolls at a minimum in order to adhere as closely as possible to ideal rolling conditions.

It is essential to good rolling conditions that the sheet or pack fit the pass provided by the working rolls. My co-pending application, above referred to, covers a mill characterized by a working pass, which with respect to a particular screw adjustment, may be varied without the necessity of replacing any of the parts of the mill. To this end the backing rolls are formed to provide spaced zones for local contact with the working rolls and the pass provided by the latter is controlled by varying relatively the diameter of the backing rolls at said zones. Such variations may be effected by the use of suitable heating and cooling equipment, the said equipment being adapted to cause the backing roll to expand or contract at said zones to the extent which may be necessary to regulate the deflection of the working rolls. The heating and cooling equipment may, for example, consist of a saddle which is arranged in contacting relation or in close proximity to each of the contact zones, the said saddle being maintained at the desired temperature by a suitable medium such as steam, hot water, oil, molten metal, et cetera.

The principal object of the present invention is to provide a backing roll of the kind generally described in which those portions of the roll which provide the contact zones are so formed that the resistance which the roll offers to expansion and contraction at said zones is minimized, whereby to increase the sensitivity of the roll to the influence of the heating and cooling equipment.

The invention is illustrated in the accompanying drawing, in which:

Figure 1 is a front elevation of a two-high mill

in which features of the invention are incorporated.

Figure 2 is an enlarged section taken along line 2—2 of Fig. 1.

Figure 3 is a view similar to Fig. 1 showing the use of one of the backing rolls in connection with each of the working rolls of the mill.

Figure 4 is a front elevation of a two-high mill in which intermediate rolls are arranged between the backing and the working rolls.

The backing roll is illustrated, by way of example, in connection with various types of two-high mills. It is to be understood, however, that the advantages of the invention may also be obtained by the use of the roll in connection with the working rolls of various kinds of multi-pass mills.

The backing roll which is indicated generally at 5 is illustrated in Figure 1 in connection with a mill which includes upper and lower working rolls 6 and 7 respectively, the said backing roll cooperating with the lower of the working rolls. The various rolls are mounted in suitable housings 8, each of which is provided with a conventional adjusting screw 9 by which the magnitude of the reductions is controlled. The backing roll, as illustrated, is formed or provided with end collars 10 and an intermediate collar 11, the latter preferably being of a suitably smaller diameter than the former. The collars provide zones for local contact with the lower working roll to limit the deflection of the latter during the reducing pass, the relative diameters of the collars determining the extent to which the lower roll is deflected, whereby the sheet or pack will be formed with a predetermined cross-sectional convexity.

The pressure exercised by the backing roll upon the associated working roll, and hence the degree of deflection of the working roll, depends among other factors upon the relative diameters of the backing roll at the points of contact with the working roll, and this factor remains constant as the temperature remains constant. It will be understood that by relatively increasing or decreasing the diameter of the intermediate section of the backing roll, i. e. in the preferred construction the diameter of the intermediate collar whereby it will be of a diameter relatively greater or relatively less than the diameters of the end collars, the deflection of the working roll will be controlled with reference to the cross-section of the sheet or pack. The variations in the relative diameters of the collars will for most purposes be of the order of a few thousandths, i. e. up to ten

or twelve thousandths, of an inch and such or other variations as circumstances may require may, therefore, be readily obtained by the use of suitable heating and cooling equipment.

5 In accordance with the invention the backing roll is so formed as to minimize the resistance which it offers to expansion and contraction of the portions thereof which provide the zones for local contact with the working roll. To this end the central collar 11 of the backing roll is provided with grooves 12 which are formed in any suitable manner. The said grooves divide the collar into a plurality of complementary segments or sections, each of which provides an independent area for contact with the working roll. The division of the collar 11 in the manner described enables relative movement between the various sections of the contact zone thereby eliminating to a large degree the constraining effect which would otherwise be present if the sectional construction were not employed. During heating or cooling of the collar 11 the sections thereof expand or contract as the case may be, the grooves 12 narrowing and widening as the said sections move toward and away from one another.

10 The grooves 12 are preferably arranged spirally or obliquely in order to insure quiet operation of the mill and prevent the backing roll from marring or otherwise injuring the working roll. 15 The width of the grooves is the minimum permitted by the groove forming operation and the depth of the grooves which in any case exceeds the width is suitable for the purposes in view, having in mind the work for which the mill is designed. The collars 10, in addition to the collar 11, may also be divided in the manner described or, if desired, the backing roll may be formed to contact with the working roll throughout its entire length, the grooves in such a case extending the full length of the roll. The peripheral segments or sections delimited by the grooves 12 will be of the same extent. The rapidity and sensitiveness of the adjustment will increase with the number of segments; the minimum number 20 of segments consistent with the requirements, is preferable.

25 In the embodiment of the invention as illustrated in Figure 3 a backing roll 5a is employed in connection with each of the working rolls 13 and 14 of the mill, the said backing rolls being similar to and functioning in substantially the same manner as the backing roll shown in Figure 1.

30 The mill illustrated in Figure 4 includes a pair of upper and lower working rolls 15 and 16 respectively. A backing roll 17 which is similar to the backing roll shown in Figure 1 is employed in connection with each of the working rolls. In this embodiment an intermediate roll 18 is arranged between the working roll 15 and the upper backing roll and a similar roll 19 is arranged between the working roll 16 and the lower backing roll. Pressure from the working rolls is transmitted to the backing rolls through the agency of the intermediate rolls. Scoring or marring, therefore, of the working rolls by the backing rolls is prevented.

35 From the foregoing it will be apparent that by forming the contact zones of the backing roll in the manner described the said zones are rendered more sensitive to the heating and cooling equipment which is employed in connection with the mill. Hence the diameter of the roll at the contact zones can be rapidly and sensitively reg-

ulated as desired. Backing rolls embodying the invention may be of any alloy or composition suitable for the work in view.

I claim as my invention:

40 1. The combination with the working roll of a mill of the character described, of a backing roll which is provided with a zone for local contact with the working roll, whereby by suitably heating and cooling the backing roll at said zone the diameter of the backing roll at said zone may be varied to control the deflection of the said working roll, said zone being divided by grooves into a plurality of complementary segments each of which provides an area for contact with the working roll, whereby to facilitate the control of the pass which is provided by the working rolls of the mill.

45 2. The combination with the working roll of a mill of the character described, of a backing roll which is provided with a zone for local contact with the working roll, whereby by suitably heating and cooling the backing roll at said zone the diameter of the backing roll at said zone may be varied to control the deflection of the said working roll, the periphery of the backing roll at said zone being grooved to divide the said zone into segments each of which is adapted to provide an area for contact with the working roll, whereby to facilitate the control of the pass which is provided by the working rolls of the mill.

50 3. The combination with the working roll of a mill of the character described, of a backing roll which is provided with a zone for local contact with the working roll, whereby by suitably heating and cooling the backing roll at said zone the diameter of the backing roll at said zone may be varied to control the deflection of the said working roll, the periphery of the backing roll at said zone being divided by grooves into segments each of which is adapted to provide an area for contact with the working roll, whereby to facilitate the control of the pass which is provided by the working rolls of the mill, said grooves being formed at a diagonal with respect to the axis of the said backing roll.

55 4. The combination with the working roll of a mill of the character described, of a backing roll which is provided with a zone for local contact with the working roll, whereby by suitably heating and cooling the backing roll at said zone the diameter of the backing roll at said zone may be varied to control the deflection of said working roll, the periphery of the backing roll at said zone being divided by grooves into segments each of which is adapted to provide an area for contact with the working roll, whereby to facilitate the control of the pass which is provided by the working rolls of the mill, said grooves being spiral in form.

60 5. The combination with the working roll of a mill of the character described, of a backing roll which is formed with a body portion spaced from the working roll and with a plurality of circumferentially arranged means for providing spaced area for local contact with the said working roll, whereby by suitably heating and cooling the backing roll at one or more of said means the diameter of the backing roll at said means may be varied to control the deflection of the said working roll, said last named means being divided by grooves into a plurality of complementary segments each of which is adapted to provide an area for contact with the working roll, whereby

to facilitate the control of the pass which is provided by the working rolls of the mill.

6. The combination with the working roll of a mill of the character described, of a backing roll which is formed with end and intermediate collars which are adapted to provide zones for local contact with the working roll, whereby by suitably heating and cooling the backing roll at said collars the diameter of the backing roll at said 10 collar may be varied to control the deflection of the said working roll, said intermediate collar being divided by grooves into a plurality of complementary segments each of which provides an area for contact with the working roll, whereby 15 to facilitate the control of the pass which is provided by the working rolls of the mill.

7. The combination with the working roll of a mill of the character described, of a backing roll which is formed with end and intermediate collars which are adapted to provide zones for local contact with the working roll, whereby by suitably heating and cooling the backing roll at said collars the diameter of the backing roll at said 20 collars may be varied to control the deflection of the said working roll, said intermediate collar being grooved to provide a plurality of complementary segments each of which is adapted to provide an area for contact with the working roll, whereby to facilitate the control of the pass which is provided by the working rolls of the 25 mill.

8. An integral backing roll for limiting to a predetermined degree the deflection of a working roll of a sheet or pack rolling mill, said backing roll being grooved to divide its periphery into segments, whereby to increase the sensitivity of the said backing roll to changes in temperature and facilitate control of its contour substantially as and for the purpose set forth. 5

9. An integral backing roll for limiting to a predetermined degree the deflection of a working 10 roll of a sheet or pack rolling mill, said backing roll being grooved along spiral or oblique lines to divide its periphery into segments, whereby to increase the sensitivity of the said backing roll to changes in temperature and facilitate control of 15 its contour substantially as and for the purpose set forth.

10. An integral backing roll for a sheet or pack rolling mill having one or more contact collars, 20 said collars being grooved so that they are peripherally segmented, substantially as and for the purpose set forth.

11. An integral backing roll for a sheet or pack rolling mill having one or more contact collars, 25 said collars being grooved so that they are peripherally segmented along spiral or oblique lines, substantially as and for the purpose set forth.

ALEXANDER PATERSON.
